UNITED STATES PATENT OFFICE.

EUGENE J. RAY, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SEWING MACHINE.

Application filed November 17, 1916. Serial No. 131,895.

To all whom it may concern:

Be it known that I, EUGENE J. RAY, a citizen of the United States, residing at Beverly, in the county of Essex and State 5 of Massachusetts, have invented certain new and useful Improvements in Sewing Machines; and I do hereby declare the following to be a full, clear, and exact description of the invention, such as will enable others 10 skilled in the art to which it appertains to make and use the same.

This invention relates to thread holding and severing mechanism for sewing machines.

15 The object of the invention is to provide a novel and improved mechanism which is well adapted for severing and holding the upper needle thread of a buttonhole sewing machine at the completion of a buttonhole, 20 and which will operate to trim the end of the thread leading from the holder to the initial part of the seam after a few stitches have been sewed at the beginning of a buttonhole.

25 To this end the invention comprises the features of construction and combinations of parts hereinafter described and referred to in the claims, the advantages of which will be apparent to those skilled in the art.

30 The invention will be readily understood from an inspection of the accompanying drawings and the following detailed description of the mechanism illustrated therein.

35 In the drawings, Figure 1 is a sectional elevation showing so much of a buttonhole sewing machine as is necessary to illustrate the application of the present invention thereto; Fig. 2 is a sectional plan view on line 2, Fig. 1; Fig. 3 is a detail front elevation, partly in section, showing the thread holding and severing mechanism; Fig. 4 is a side elevation looking toward the right in Fig. 3; Fig. 5 is a plan view of the parts shown in Figs. 3 and 4; Figs. 6 to 11 are detail views showing the mode of operation of the devices in severing, holding and trimming the thread; Fig. 12 is a longitudinal sectional view through the bearing, in which the holder and cutter bars are mounted; Fig. 13 is a detail view of the thread holder bar; Fig. 14 is an end view of the bar looking toward the right in Fig. 13; Fig. 15 is a detail plan view of the

cutter bar; and Fig. 16 is an end view of 55 the bar, looking toward the right in Fig. 15.

In the drawings the invention is shown as embodied in a buttonhole sewing machine having the construction and mode of operation of the machine shown and described in Patent No. 1,063,880, dated June 3, 1913. In this machine the stitch forming mechanism comprises an upper needle 2 eccentrically mounted in a vertically reciprocating needle bar 4, an under needle 6 and 60 a looper 8. The upper needle bar and the under needle and looper are mounted respectively in a rotary carrier 10 and a rotary turret 12 which are rotated during the sewing about the eye and end of the 70 buttonhole. The work is held by two work clamping feet 14 pivotally mounted on the ends of clamp arms 16, which are in turn pivoted to supporting blocks 18. The blocks 18 are secured upon work supporting 75 plates 20, which are pivoted at 22 to the clamp carriage 24, so that the plates and clamps may be separated or moved laterally to spread the buttonhole. The clamp arms 16 are moved vertically to close and 80 open the clamps at the proper times by mechanism which forms no part of the present invention. The clamp carriage is moved longitudinally to bring the work into register with the buttonhole cutter 26, 85 or into register with the stitch forming mechanism, and to feed the work during the sewing, by a cam groove formed in the cam gear 28 which makes one revolution for 90 each cycle of the machine. The clamp carrier is moved laterally, and the stitch forming mechanism is rotated during the sewing through suitable connections from a gear 30 which makes one revolution during the 95 sewing of a buttonhole.

At the completion of the sewing of the buttonhole the stitch forming mechanism is stopped with the upper and under needles in retracted positions, and with the loop of upper needle thread held by the looper as 100 indicated in Fig. 1. The upper needle thread is then automatically severed and the end of the needle thread is held, preparatory to the beginning of the next sewing operation. After the initial stitches 105 have been formed, and the thread is anchored in the seam, a cutter blade is operated to cut the thread leading from the seam

to the holder close to the work. In the construction shown, the devices for thus severing, holding and trimming the thread comprise two semi-cylindrical bars 32 and 34 mounted to reciprocate in a bearing 36 formed on the right-hand clamp foot 14. The bars are mounted one above the other, and the forward end of the upper bar 32 is flattened and provided with a laterally projecting thread engaging finger or hook 38. After the stitch forming mechanism has stopped at the completion of a button-hole, the bar 32 is advanced from the position indicated in Figs. 3 and 12 to the position indicated in Figs. 5 and 6, and as it advances, the thread finger 38 deflects the standing thread, which immediately springs into position back of the finger after the finger has passed, as indicated in Figs. 1 and 9. The bar 32 is then quickly retracted, and carries the thread laterally under a spring plate 40 which co-operates with the upper surface of the thread finger in gripping and holding the thread. The thread finger also carries the thread against a cutting edge or blade 42 formed on the forward end of the bar 34, and arranged to co-operate with the lower edge of the thread finger in severing the thread, as indicated in Fig. 7. The thread holding devices are preferably so arranged with relation to the sewing point that the thread leading from the holder to the initial needle hole at the beginning of the next sewing operation will be so held that the initial stitches will cover the thread. After several stitches have been made at the beginning of the sewing operation the cutter bar 34 is advanced, and a cutter blade 44, which is formed on the forward end of the bar at its lower edge, and is arranged to project beyond the cutter blade 42, engages the thread close to the seam, and thus closely trims the thread end retained by the thread holder. In order that the cutter blade 44 may cut the thread close to the seam, without danger of injuring the stitches of the seam, guard flanges 46 are formed at the sides of the blade which extend slightly below its edge, so that they may ride over and press down the seam as the blade passes across it. The bearing in which the thread holder and the cutter bar reciprocate is preferably formed at an inclination to the surface of the work as indicated, since this arrangement enables the standing thread to be severed and held comparatively close to the work, and also enables the trimming blade to pass close to the seam in trimming the waste end of thread.

In the construction shown, the thread holder and cutter bars are held in retracted position by springs, and are advanced and released at the proper times by devices actuated through the longitudinal travel of the

clamp carriage. As shown, the thread holder bar 32 is provided with a shank projecting through a plate 48 which closes the rear end of the bearing 36, and the bar is held in retracted position by a spring 50 surrounding the shank and interposed between the plate and a nut 52 on the rear end of the shank. The bar is advanced through a rock shaft 54 mounted to turn on a stud 56, and provided at its lower end with a gear segment 58 engaging a rack 60 formed on the side of the bar. A collar 62 is secured upon the upper end of the shaft, and is provided with a radially projecting finger 64 mounted to engage a relatively stationary dog 66 during the travel of the clamp carriage (Figs. 4 and 5). The dog 66 is held in the path of the finger 64 by a spring 68, and is provided with an incline 70 at its end against which the finger rides during the forward travel of the clamp carriage. The finger 64 will therefore force the dog 66 back out of its path during the forward travel of the clamp carriage, and as soon as the finger has passed, the dog will immediately snap forward into position to engage and operate the finger during the return movement of the carriage. The engagement of the finger with the dog during the return movement of the carriage to cutting position after the sewing has been completed will rock the sleeve 54 and thus advance the thread holder bar into position to engage the thread, after which the continued movement of the clamp carriage will free the finger from the dog, so that the thread holding bar may be quickly retracted by the spring 50 to sever and grip the thread as above described.

A similar mechanism is provided for reciprocating the cutter bar 34. The bar is provided on its side with a rack 72 engaged by a gear segment 74 on the lower end of a rock shaft 76 which is mounted in a bearing 78 on the clamp foot 14. A collar 80 is secured to the upper end of the rock shaft, and is provided with a radially projecting finger 82 arranged to engage a spring-pressed dog 84 similar to the dog 66 but facing in the opposite direction. A torsional spring 86 is connected to the bearing 78 and to the collar 80, and acts to normally hold the bar 34 in retracted position with its rear end against the plate 48, as indicated in Figs. 3 and 12. During the forward movement of the clamp carriage the dog 84 acts on the finger 82 and rocks the shaft 76 to advance the cutter bar and trim the waste end of thread as above described. During the return movement of the clamp carriage, however, the finger forces the dog back and rides idly past the dog.

In order that the dogs 66 and 84 may be maintained continually in proper relation to

the fingers 64 and 82, which are mounted on and moved with the clamp, the dogs are carried in a support 88 which is mounted to move laterally and vertically with the 5 clamp, and is connected therewith by interlocking guiding devices. As shown, the support is mounted to move vertically about a horizontal pivot 90 carried by a head 92. The head is provided with a trunnion 94 10 mounted to turn in a vertical bearing 96 formed on a bracket 98 secured to the head of the machine. The weight of the support 88 is counterbalanced by a spring 100. The support is connected to move laterally and 15 vertically with the clamp by a guide stud 102 projecting from the upper end of the collar 80 into a guideway 104 formed in the lower side of the support.

The dogs 66 and 84 are mounted in bearings 106 which are adjustably secured in brackets 108 by set screws 110, so that the dogs may be adjusted across the path of the fingers 64 and 82 to vary the movements imparted to the holder and cutter bars. 20 The brackets 108 are adjustably secured on the support 88 by clamping screws 112, so that the dogs may be adjusted along the path of travel of the fingers to vary the points in the travel of the clamp carriage at which 25 the bars will be advanced and retracted.

While it is preferred to employ the specific construction and arrangement of parts shown and described, particularly in embodying the invention in the machine of the 30 patent above referred to, it will be understood that this construction and arrangement is not essential to the broader features of the invention, and may be varied or modified as found desirable or best suited to the construction and arrangement of the parts and mechanisms of the machine in which it is to 35 be embodied.

Having explained the nature and object 40 of the invention, and specifically described one form of mechanism in which it may be embodied, what is claimed is:—

1. A sewing machine, having, in combination, stitch forming mechanism for sewing an overseam, means for holding the thread 45 end at the beginning of the sewing in position to be covered by the initial stitches of the seam, and means for trimming the uncovered end of the thread.

2. A sewing machine, having, in combination, stitch forming mechanism for sewing an overseam, thread severing and holding devices for severing the needle thread at the end of the sewing and for holding it in 50 position to be covered by the initial stitches at the beginning of the succeeding seam, and a cutter for cutting the uncovered end of the thread close to the seam.

3. A sewing machine, having, in combination, a work clamp, stitch forming mechanism, 55 means operated by the relative travel

of the clamp and stitch forming mechanism to sever and hold the thread after the completion of the sewing, and means for severing the thread between the holder and work at the beginning of the sewing.

4. A sewing machine, having, in combination, stitch forming mechanism, an endwise reciprocating bar provided with a thread engaging finger projecting laterally of its longitudinal axis for engaging and carrying the thread laterally at the completion of the sewing, thread clamping and severing members against which the finger carries the thread, and a second thread severing member below the first for severing the thread leading from the holder to the seam at the beginning of the sewing.

5. A sewing machine, having, in combination, stitch forming mechanism, a thread holder bar provided with a thread engaging finger, a cutter bar underlying the holder bar and provided with an upper edge for co-operating with the thread finger in severing the thread and with a lower cutting edge for cutting the thread close to the work, and mechanism for actuating the holder and cutter bars.

6. A sewing machine, having, in combination, stitch forming mechanism, a reciprocating holder bar provided with a thread engaging finger, a co-operating clamping member, a reciprocating cutter bar provided with an upper edge co-operating with the thread finger and a lower edge for cutting the thread close to the work, and mechanism 95 for actuating the bars.

7. A sewing machine, having, in combination, stitch forming mechanism, a support provided with a guideway, two superposed bars mounted to reciprocate in the guideway, a thread holding finger at the forward end of the upper bar, two cutting edges at the forward end of the lower bar, mechanism for actuating the upper bar to sever and hold the thread at the completion of the sewing, 105 and mechanism for actuating the lower bar to sever the end of the thread at the beginning of the sewing.

8. A buttonhole sewing machine, having, in combination, a work clamp, stitch forming mechanism, a thread severing and holding device for severing and holding the thread after the stitching of a buttonhole is completed, a thread cutting blade for cutting the thread after the stitching of a buttonhole has begun, and mechanism for actuating the holding and severing devices and the blade by the relative movement of the stitch forming mechanism and work clamp.

9. A buttonhole sewing machine, having, 125 in combination, stitch forming mechanism, a traveling clamp carriage, a clamp arm on the carriage, thread severing and holding devices on the clamp arm, a vertically movable support, dogs on the support, actuating 130

mechanism for the thread severing and holding devices engaged with the dogs by the travel of the carriage, and guiding devices on the support and clamp for maintaining the parts in co-operative relation.

10. A buttonhole sewing machine, having in combination, stitch forming mechanism, a traveling and laterally movable clamp, thread severing and holding devices on the clamp, a support mounted for lateral movement with the clamp, co-operating devices on the clamp and support for actuating the severing and holding devices through the travel of the clamp, and guiding devices on the support and clamp for maintaining the actuating devices in operative relation.

11. A sewing machine, having, in combination, stitch forming mechanism, thread holding and severing devices for holding and severing the thread at the completion of the sewing, and a reciprocating blade for severing the thread close to the seam at the beginning of the sewing provided with guard flanges for riding over the seam.

12. In a sewing machine constructed to sew a succession of short seams and to come to rest at the end of each seam, the combination with stitch-forming mechanism and work-holding means movable relatively to each other, of means adapted to take and hold the needle thread between the needle and the work, thread-trimming means

adapted to sever the thread between the holding means and work, and means rendered operative by such relative movement to cause the thread-holding means to take the needle thread after the completion of one seam and to hold it while the thread is severed and while a second seam is thereafter begun to be stitched, and also to cause the thread-trimming means to cut the thread both at the end of each seam and after the starting of the stitching on the next seam.

13. In a sewing machine constructed to sew a series of short seams and come to rest after each seam, the combination of stitch-forming mechanism and work-holding means movable relative to each other, thread-gripping means adapted to take and hold the needle thread between the needle and the work, thread-trimming means adapted to sever the thread between the thread-stripping means and the work, and means operated by such relative movement to cause the gripping means to take the thread and the trimming means thereafter to sever it in the period between the completing of one seam and the starting of the next seam, and to cause the trimming means thereafter and after the starting of said next seam to trim the thread end held by the gripping means.

EUGENE J. RAY.
